UNITED STATES PATENT OFFICE.

THOMAS P. BOLGER, OF GLOUCESTER, MASSACHUSETTS.

REFRIGERATOR CONSTRUCTION.

1,209,544.

Specification of Letters Patent. Patented Dec. 19, 1916.

Application filed March 2, 1916. Serial No. 81,693.

To all whom it may concern:

Be it known that I, THOMAS P. BOLGER, a citizen of the United States, residing at Gloucester, in the county of Essex, State of Massachusetts, having invented a new and useful Refrigerator Construction; and I do hereby declare the following to be a full, clear, and exact description of the invention, such as will enable others skilled in the art to which it appertains to make and use the same.

The present invention relates to certain new and useful improvements in the construction of sheet metal refrigerators, and has for its object to provide a novel means for fastening the edges of the metal lining and outside metal covering in the door opening whereby a tight joint is obtained when the door is closed and a continuous metal wall for conducting heat from the outside to the inside of the refrigerator is avoided.

Further objects of the invention are to provide a construction of this character which is simple and inexpensive, which breaks up any possible air passage around the edge of the door, which securely fastens the edges of the sheet metal lining and cover without bringing them together in such a manner as to provide a continuous metal wall between the outside and the inside of the refrigerator, and which does not interfere in any manner with the opening and closing of the door.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a horizontal sectional view through the front portion of a refrigerator constructed in accordance with the invention, the door thereof being shown in a closed position by solid lines and in an open position by dotted lines. Fig. 2 is a detail sectional view taken at the hinged side of the door.

Corresponding and like parts are referred to in the following description and indicated in all the views of the drawing by the same reference characters.

Specifically describing the present embodiment of the invention, the numeral 1 designates the frame or body of the refrigerator, said frame being formed of some good heat insulating material such as wood, and preferably being constructed with outer and inner walls having an air space between the same. The door frame 2 is also preferably formed of some good heat insulating material such as wood, the door being mounted upon hinges 3 so as to swing into and out of the door opening 4. This door opening 4 is formed with an outwardly facing annular shoulder 5, while the door 2 is constructed with an annular flange 6 having an opposed relation to the shoulder 5 of the door opening.

The inside lining 7 of the refrigerator is preferably what is known as a one-piece porcelain lining. This lining 7 is formed with a flange 8 which projects into the door opening 4 and terminates in a comparatively narrow lip 9 fitting over the inner edge of the shoulder 5. The outside sheet metal covering 10 is formed with a flange 11 which projects into the door opening 4 and terminates in a lip 12 fitting against the outside portion of the shoulder 5. The lip 9 of the inside lining 7, and the lip 12 of the outside covering 10 are both in the same plane, and both fit squarely against the shoulder 5, although they are spaced from each other so as to avoid a continuous metal wall from the outside to the inside of the refrigerator. A strip of irregular molding 13 is secured to the shoulder 5 and extends over the lips 9 and 12 in such a manner as to clamp them securely against the shoulder and protect them against injury. The fastening members or screws 14 which are employed for securing the molding 13 in position enter the shoulder 5 between the edges of the lips 9 and 12 and are spaced therefrom so as to prevent a continuous metal heat conducting path being established through the sheet metal and screws. The outer face of the molding 13 has a rounded lip 13^a projecting from the inner side thereof, while the outer side thereof is provided with a correspondingly shaped groove or depression 13^b.

The inner face of the door 2 is covered with a sheet metal lining 15 provided at the edges thereof with flanges 16 extending around the edges of the door, and terminat-

ing in lips 17 fitting against the door flange 6. In an analogous manner the outside covering 18 for the door 2 is formed with a peripheral flange 19 extending around the edge of the door and terminating in a lip 20 which fits against the inner face of the door flange 6. The lips 17 and 20 have a spaced relation so as to prevent the establishment of a continuous metal heat conducting wall between the outside and the inside of the refrigerator. A strip 21 of irregular molding is applied to the inner face of the door flange 6 in such a manner as to clamp the sheet metal edges 17 and 20 securely in position, the fastening members or screws 22 entering the flange 6 between the sheet metal lips 17 and 20 and being spaced therefrom. The molding 21 upon the flange of the door has an opposed and complementary relation to the molding 13 which is applied to the shoulder of the door opening. This molding 21 is formed upon one side thereof with a longitudinal rib 21^a adapted to enter the depression 13^b of the molding 13, and at the opposite side thereof with a depression or groove 21^b adapted to receive the rib 13^a of the molding 13. A layer 24 of insulating material, such as waterproof paper, is interposed between the sheet metal lining and covering and the wooden frame, thereby obtaining better insulation.

When the door is closed the irregular molding 21 upon the door flange 6 fits against and interlocks with the irregular molding 13 upon the shoulder 5 of the door opening, thereby interrupting any possible air passage around the edge of the door and obtaining a tight joint between the door and the body of the refrigerator. At the same time, it will be observed that there is no continuous metal wall between the inside of the refrigerator and the outside of the refrigerator, since the edges of the inside sheet metal lining members and outside sheet metal covering members are clamped under the strips of irregular molding and held in a spaced relation from each other. This is quite important in the construction of sheet metal refrigerators, since metal is an excellent conductor of heat, and where there is a continuous metal wall between the outside and the inside of the refrigerator, heat is conducted into the refrigerator to such an extent as to very materially decrease the efficiency thereof. The effect of almost perfect insulation in the body of the refrigerator may be destroyed by a construction providing continuous metal walls between the outside and inside of the refrigerator at the door opening. With this construction the edges of the sheet metal are clamped securely in position in a very inexpensive manner and, at the same time, they are held in a spaced relation to each other. The strips of molding which are employed for clamping

the edges of the sheet metal in position are also constructed in such a manner as to interlock with each other and break up any air passage around the edge of the door. In this connection it will be noted that the inclination between the base of the groove 13^b of the molding 13 and the top of the lip 13^a, at the hinge end of the door, is substantially on the arc of a circle having the pivots of the hinges 3 as a center to admit of the door opening and closing without binding. 75

Having thus described the invention, what I claim as new and desire to secure by Letters Patent, is:—

1. A refrigerator including a body having a door opening, a swinging door hinged to the body and adapted to close the door opening, a sheet metal lining applied to the body and having the edges thereof carried into the door opening, a sheet metal outer covering applied to the body and also having the edges thereof carried into the door opening, strips of non-heat conducting molding applied to the sides of the door opening and fitting over the edges of the sheet metal lining and sheet metal outer covering, said edges being held in a spaced relation to each other so that there is no continuous metal wall between the outside and the inside of the refrigerator, and corresponding strips applied to the door for engagement with the strips of the door opening to form a tight joint when the door is closed. 80

2. A refrigerator including a body having a door opening, a swinging door hinged to the body and adapted to close the door opening, a sheet metal lining applied to the body and door and having the edges thereof carried into the door opening and around the edges of the door, respectively, a sheet metal outer covering applied to the body and door and having the edges thereof carried into the door opening and around the edges of the door, respectively, and spaced from the corresponding edges of the lining, and corresponding strips of non-heat conducting molding applied to the sides of the door opening and the edges of the door, respectively, said strips holding the edges of the lining and the outer covering in a spaced relation to each other so that there is no continuous metal wall between the outside and the inside of the refrigerator, and engaging each other to form a tight joint when the door is closed. 100

3. A refrigerator including a body having a door opening formed with an outwardly facing shoulder, a door formed with a flange, a sheet metal lining applied to the body and door and formed with lips at the edges thereof fitting against the shoulder of the door opening and the flange of the door, respectively, a sheet metal outer covering applied to the body and door and provided at the edges thereof with lips fit- 110

ting against the shoulder of the door opening and flange of the door, respectively, and spaced from the corresponding lips of the lining, and corresponding strips of non-heat 5 conducting molding applied to the shoulder of the door opening and flange of the door, respectively, said strips engaging each other to form a tight joint when the door is closed and clamping the lips of the lining and outer 10 covering in a spaced relation to each other so that there is no continuous metal wall between the outside and the inside of the refrigerator.

4. A refrigerator including a body having 15 a door opening formed with an outwardly facing shoulder, a door formed with a flange, a sheet metal lining applied to the body and door and provided at the edges thereof with lips fitting against the shoulder of the door 20 opening and flange of the door, respectively, a sheet metal outer covering applied to the body and door and provided at the edges thereof with lips fitting against the shoulder of the door opening and flange of the door, respectively, and corresponding strips of 25 non-heat conducting molding applied to the shoulder of the door opening and flange of the door, respectively, said molding clamping the lips of the lining and outer covering 30 in position and holding them in a spaced relation to prevent the formation of a continuous metal wall between the outside and the inside of the refrigerator, and the opposed

faces of the strips of molding being formed with corresponding ribs and grooves. 35

5. A refrigerator including a body having a door opening formed with an outwardly facing shoulder, a door formed with a flange, a sheet metal lining applied to the body and door and having the edges thereof extended 40 into the door opening to the shoulder and around the edges of the door to the flange, a sheet metal outer covering applied to the body and door and having the edges thereof extended into the door opening to the shoulder 45 and around the edges of the door to the face of the flange, and corresponding strips of non-heat conducting molding applied to the shoulder of the door opening and the face of the door flange so as to secure the 50 edges of the sheet metal lining and sheet metal outer covering in a spaced relation and prevent the formation of a continuous metal wall between the outside and the inside of the refrigerator, said strips of molding upon 55 the shoulder and door flange fitting against each other to form a tight joint when the door is closed.

In testimony whereof I have signed my name to this specification in the presence of 60 two subscribing witnesses.
